UNITED STATES PATENT OFFICE.

HULBERT P. HOLDEN, OF SPRINGFIELD, MASSACHUSETTS.

DUST COLLECTOR.

Application filed May 27, 1922. Serial No. 564,097.

To all whom it may concern:

Be it known that I, HULBERT P. HOLDEN, citizen of the United States, residing at Springfield, in the county of Hampden and State of Massachusetts, have invented new and useful Improvements in Dust Collectors, of which the following is a specification.

This invention relates to dust collectors and more particularly to dust collectors for the confining of dust caused by the transferring of ashes into a container.

One object of the invention is to provide a device of this character wherein the result is accomplished without the assistance of any external devices or appliances other than those wholly contained within itself.

Another object is to provide a dust collector or a dustless ash chute of neat and attractive design which is simple and inexpensive to construct and positive in operation.

Another object is to provide a dust collector which is characterized by the novel action of the different elements and by the construction and arrangement of the different parts as hereinafter described.

My device is particularly adapted for household or domestic use in connection with the usual barrel or can for the reception of ashes and while in the present embodiment it is shown in a preferred form, it is understood that the scope of the invention is defined by the appended claims.

In the drawings,

Fig. 1 is a front elevation of the device;

Fig. 2 is a vertical cross-section taken through the center of the dust collector along line A—A of Fig. 1;

Fig. 3 is a sectional view taken on the line 3—3 of Fig. 2;

Fig. 4 is a detail section of some of the parts shown in Fig. 2, with the closure in open position;

Fig. 5 is a perspective view looking at the rear of the device.

Referring to the drawings the dust collector comprises a hood preferably with a substantially wedge shape outline formed by vertical side walls 1, 1, an upper front wall 2, a lower front wall 3, and a rear wall 4 set in a circular flanged cover 5 adapted to be supported on an ash can, the vertical sides of which are shown in dotted lines at 6—6 in Fig. 2. The interior of the cover 5 is cut away to provide a sufficiently large opening for the bottom of the hood and also to allow

a wide enough circular seat for resting the hood on the top edge of ash cans of various sizes. The side walls 1, 1, rear wall 4 and lower front wall 3 are joined to the cover 5 in any suitable manner as by crimping their edges to the corresponding interior edges of the cover and soldering same so as to insure substantially air tight joints and a stable support for the walls upon the cover. The walls are joined together likewise along their respective adjacent edges. The seat on the under side of the cover is lined with packing 7 to provide an air tight connection with the ash can.

At the front of the hood is an inclined chute 8 provided with a ceiling 9, floor 10, and sides 11, 11. The ceiling 9 and sides 11, 11 are preferably formed as an extension from the upper front wall 2, the sides 11, 11 providing shoulders 12, 12 at their inner edges on the side walls 1, 1 of the hood and the ceiling 9 terminating in a shoulder 13 at its lower edge. The floor 10 is joined to the upper edge of the lower front wall 3 forming a ledge 24 and provides a shoulder 14 at its lower edge. The several shoulders 12, 12, 13, and 14 thus described bound the edges of the inlet opening at the lower end of said chute 8 and serve to form a seat for a closure or door 15.

The door or closure 15 pivotally hinged to the side walls, 1, 1 by pivot pins 16 passing therethrough is arranged to close the opening at the lower end of chute 8 formed by the shoulders 12, 12, 13 and 14 above described. The door 15 is constructed so that its hinged joint is substantially air-tight at all times and is provided with side flanges 17, 17 to which are attached felt strips 19 contacting with the sides 1, 1. The shoulders 12, 12, 13 and 14 are also preferably lined with felt strips 20 against which the door 15 rests when in closed position. This construction provides a substantially air-tight closing of the chute 8 when the door 15 is in closed position and provides an entrance at the bottom of the chute substantially restricted to the passage of ashes when the door is opened by a charge of ashes entering said hood. The door 15 is provided with means to automatically close same which consists preferably of balanced weights 21 attached to each side edge of the same as shown. The door 15 is also provided at its lower edge with a flange 18 to which is flexibly attached a contact flap 110

22 which lies upon an extension 23 of the lower front wall 3 and slightly overlaps same when the door is in closed position. The function of said flap 22 cooperating with the 5 extension 23 is to assist in maintaining a substantially closed condition of said inlet opening against the egress of dust during the passage of said charge of ashes into said hood.

10 At the rear of the hood a relatively large rectangular opening is defined by the edges of the side walls 1, 1, rear wall 4 and the upper front wall 2 which at all times is closed by a covering 20' of a light flexible material 15 attached to the four edges of said opening forming a chamber 21 within the hood. The covering 20' hangs loosely from the edges of said walls into the hood and forms a movable wall for said chamber 21 allowing the 20 same to expand and contract under slight changes in air pressure within the hood. The material of which the covering 20' is made is preferably of light fabric substantially impervious to dust but which will allow 25 low air to slowly permeate therethrough and at the same time its texture is such that it will confine sudden displacements of air within the chamber 21. In order to arrange the movable wall or covering 20' so as to be 30 readily responsive to slight variation of air pressure within the hood, it is preferably hung between supports one above the other so as to furnish an extensive vertically hung portion as shown. This arrangement allows 35 the covering 20' to serve as a self-cleaning baffle for the dust collecting thereon and being hung over the container permits the dust to drop therein.

40 A grid or cover 25 may be provided for the rear movable wall of the hood to protect the covering 20' from injury and handles 26 are preferably attached to the side walls 1, 1 which allow convenient handling of the device. A brace 27 is also 45 preferably provided extending between the flange of the cover 5 and the lower front wall 3 to reinforce the latter.

50 In operation the door or closure 15 is moved inwardly by the ashes sliding down the chute 8 and is opened to allow the ashes to fall off the extension 23 into the container. This opening movement of the door 15 sets up an air wave within the chamber 21 which acts upon the covering 20' forming 55 the movable wall causing it to move outwardly and expand the chamber 21. This outward movement of wall 20' is further assisted by the displacement of air within the chamber caused by the volume of ashes 60 entering said chamber. This pressure or displacement of the air within the chamber 21 is relieved by the outward movement of the covering 20'. Unless there is a means by which this displacement of air is allowed 65 for, the air thus displaced will seek an egress

through the entrance through which the ashes are passing. The flap is arranged so that it will fit closely around the entering ashes thereby maintaining a substantially closed condition of the opening against the 70 egress of dust while the ashes are entering the receptacle. Thus by the action of the expansible chamber and the arrangement of the door and flap any dust within the chamber will be prevented from escaping. 75 Before the chamber 21 starts to contract by reason of the covering 20' falling back to its normal position or any out draft of air is set up adjacent the door opening, the door 15 is automatically closed by the weights 80 21 thereby preventing the escape of dust within the hood. The employment of the flexibly hinged flap 22 at the lower edge of the door 15 has the advantage both of maintaining the closed condition of the chute inlet opening during the initial opening movement of the door 15 and also of maintaining a closed condition of the opening against the egress of dust while the ashes are falling 85 into the container. Finally when the last portion of the ash mass has fallen off the extension 23 there is created a slight suction 90 into the container caused by air following in behind the ash mass which will carry with it any dust adjacent the opening at this 95 point of the operation.

There is thus provided a device in which the opening is substantially closed at all times; the closure being opened only far enough to allow the ash mass to enter and the ash mass itself with the help of the flap closing the opening at this time; and in which the displacement of air caused by the initial opening movement of the door and the ash mass falling into the container is allowed for so that all the dust is collected 100 in the hood.

It is obvious that while the preferred form of the invention as shown is adapted for use with containers of the ash can or barrel type it may be used with other type containers and is peculiarly adapted for use with ash sifters.

What I claim is:

1. A dust collector comprising an enclosing hood having an inlet opening for a charge of material, a closure for said opening, said hood provided with means to form an expansible closed chamber therein adapted to allow for the displacement of air within said hood caused by said charge of material entering said hood thru said opening, said closure comprising means to maintain a substantially closed condition of said opening against the egress of dust during the passage of said charge of material there thru.

2. A dust collector comprising an enclosing hood having a flexible wall forming an expansible chamber therein, an inlet open-

- ing in said hood for a charge of material, a closure for said opening comprising means to maintain a substantially closed condition of said opening against the egress of 5 dust during the passage of said charge of material entering said hood thru said inlet opening.
3. A dust collector comprising an enclosing hood having a flexible wall forming 10 an expansible chamber therein, an inlet chute for conducting a charge of material into said hood, an inwardly opening door for said chute arranged to coact with the walls of said chute to maintain a substantially closed condition of said chute against 15 the egress of dust during the passage of said charge of material therethru.
4. A dust collector comprising an enclosing hood having a flexible wall forming 20 an expansible chamber therein, an inlet chute for conducting a charge of material into said hood, an inwardly opening door for said chute arranged to coact with the walls of said chute to maintain a substantially closed condition of said chute against 25 the egress of dust during the passage of said charge of material therethru, and means to automatically shut said door after the passage of said charge of material thru said opening. 30
5. A dust collector comprising an enclosing hood having a movable wall of light fabric substantially impervious to dust forming an expansible chamber within said hood, 35 an inlet opening in said hood for a charge of material, a closure for said opening comprising means to maintain a substantially closed condition of said opening against the egress of dust during the passage of said 40 charge of material entering said hood thru said inlet opening.
6. A dust collector comprising, an enclosing hood having a movable wall of light fabric hung in a loose sagging fold between 45 upper and lower points of support and forming an expansible chamber within said hood, an inlet opening in said hood for a charge of material, a closure for said opening comprising means to maintain a substantially closed condition of said opening, 50 against the egress of dust during the passage of said charge of material entering said hood thru said inlet opening.
7. A dust collector comprising an enclosing hood having a flexible wall forming an 55 expansible chamber therein, a downwardly and inwardly inclined inlet chute with an opening at its lower end for conducting a charge of material into said hood, a pivotally hung door for the lower end of said chute, said door normally being inclined from the vertical with its lower edge toward the mouth of said chute and arranged to coact with the walls of said chute to maintain 60 a substantially closed condition of said 65 chute against the egress of dust during the passage of said charge of material therethru.
8. A dust collector comprising an enclosing hood having a flexible wall forming an 70 expansible chamber therein, a downwardly and inwardly inclined inlet chute with an opening at its lower end for conducting a charge of material into said hood, a pivotally hung door for the lower end of said chute, said door normally being inclined from the vertical with its lower edge toward the mouth of said chute and arranged to coact with the walls of said chute to maintain a substantially closed condition of said chute against the egress of dust during the passage of said charge of material 75 therethru, and means to automatically shut said door after the passage of said charge of material thru said opening. 80
9. A dust collector comprising an enclosing hood having a flexible wall forming an 85 expansible chamber therein, a downwardly and inwardly inclined inlet chute with an opening at its lower end for conducting a charge of material into said hood, an inwardly opening door for said chute opening, a flexible flap connected to the lower edge of said door, said door and said flap arranged to coact with the walls of said chute to maintain a substantially closed condition of said chute opening against the egress of dust during the passage of said charge of material therethru. 90
10. A dust collector comprising an enclosing hood having a downwardly and inwardly inclined inlet chute with an opening at its lower end for conducting a charge of material into said hood, an inwardly opening door for said chute opening, a flexible flap connected to the lower edge of said door, said door and said flap arranged to coact with the walls of said chute to maintain a substantially closed condition of said chute opening against the egress of dust during the passage of said charge of material therethru. 95
11. A dust collector comprising an enclosing hood, an inclined chute with an opening at its lower end into said hood, said chute having a bottom extension into said hood beyond said opening, a movable closure for said chute opening having a flexibly connected flap for contact with said bottom extension, said hood having an expansible chamber adapted to expand upon each opening movement of said closure. 100
12. A dust collector comprising a circular base, and a substantially wedge-shaped hood, a downwardly inclined chute extending 105 110 115 120 125 130

through one inclined side wall of said hood and having an opening at its lower end into said hood, a movable closure for said chute opening, a movable wall of light fabric hung loosely at the other side of said hood upon supports adjacent the apex and base of said hood, said movable wall forming an ex-

pansible chamber for said hood adapted to expand upon each opening movement of said movable closure. 10

In testimony whereof I have affixed my signature.

HULBERT P. HOLDEN.
